ARTICLE PROJECTION APPARATUS FOR SHELVES

William V. Waxgiser, Brooklyn, N. Y.

Application October 28, 1935, Serial No. 46,997

6 Claims. (Cl. 312—71)

The present invention relates to means applicable to shelves for moving forwardly rows of packages such as tins and canisters, and for discharging the foremost tin on a shelf to a holder projected forwardly of the shelf, and in position for convenient removal by an operator.

A further object of the invention is to provide means of the character described, applicable to either steel shelving as a built-in combination, or, to wooden shelving, as an attachment therefor.

Other objects of the invention will hereinafter appear.

The invention will be described with reference to the accompanying drawings, in which:—

Figure 1 is a top perspective view, partly broken away, of a shelf section having an embodiment of the invention.

Figure 2 is a bottom perspective view of the structure illustrated in Figure 1.

Figure 3 is a transverse section on the line 3—3, Figure 1.

Figure 4 is a plan view, partly broken away, and partly in dotted lines, showing a modified form of the invention.

Figure 5 is a fragmentary vertical section on the line 5—5, Figure 4.

Figure 6 is a longitudinal section on the line 6—6, Figure 5, looking in the direction of the arrows.

Figure 7 is a view similar to Figure 6, showing certain supporting elements moved outward.

Figure 8 is a plan view of the elements shown in Figure 7.

In Figures 1 to 3 inclusive, I have shown a form of the invention in which a steel shelf 1 having front and rear flanges 2, has applied thereto a plurality of rectangular frame members 3, the front and back ends thereof being respectively indicated at 3x and 3xx. Frame members 3 rest upon the top of the shelf 1 and each element may be provided with a pull handle 4. It is to be noted that front flange 2 of the shelf is formed with a plurality of spaced apertures which receive a plurality of rods 5 which may be formed of bent wire, the wire being bent upwardly at the front flange to provide a stop member 5xx. One of the rod sections at its inner end is angularly bent at 5x to provide a stop which may abut against a flange bar 6 secured to the underface of the shelf, and apertured for the rods.

The frames 3 are preferably arranged side by side and in mutual contact, and the side mem-

bers of each frame are so spaced as to receive a canister 7 of specific diameter.

When the device is at rest, rows of canisters will be bounded, as to each row, by one of the frames 3. When it is desired to remove a can from any one row, the appropriate frame member is moved outwardly by its handle, thus contacting with the rearmost can and moving forwardly the row, the foremost can striking the stop member 5xx and moving the rods connected thereto outwardly until the angularly bent end 5x thereof strikes flanged bar 6. At this moment, the can will reach a position at which its inner edge will have passed over the front of the shelf, and the can will drop downwardly to be held by the underlying rods connected to stop member 5xx. When the can is removed, the frame may be pushed rearwardly and in its rearward movement will contact with stop member 5xx, restoring it to initial position.

In the structure of Figures 4 to 8 inclusive, the wooden shelf 8 is provided longitudinally thereof and near its front, with a plate 9 having longitudinally extending flanges 10, 10x. The frames are of the same construction as in the preceding form of the invention, and bear the same numeral, to wit, 3.

Passing through apertures formed in the flanges 10, 10x, and one for each frame member, is contact member 11 of wire bent into U-shaped formation at an intermediate point, and extending vertically, and thence having its ends extending horizontally through said flanges. One of the horizontally extending ends of member 11 is angularly bent at 11x and in line therewith is the end 12x of a contact member 12, having a vertically extending angularly bent section within a similarly bent section of member 11. Also, within member 12 is a similarly bent but smaller contact member 13, having its horizontally extending sections 13a of shorter length than the corresponding elements of member 12, and also within the path of movement of bent end 11x carried by member 11, is bent end 13x.

In the operation of this modified form of device, it will be noted that each frame member initially embraces a row of cans, and that the rear transversely extending portion of the frame member, will, upon movement of the member, contact with the rearmost can and in the continued movement will carry the foremost can into engagement with contact member 11. The bent end 11x, will, after a short movement of member 11, contact with a horizontal end section of member 12 and cause movement of the

latter. Member 12 lies immediately under the top of supporting surface of the shelf 8 and therefore it will follow the can as a support therefor during a forward movement of the can.

5 As the can moves forwardly, and just before it is moved beyond the shelf 8, bent end member 11x will contact with one of the horizontal rod-like ends of member 13, and that member finally will be moved to the position shown in Figure 8, 10 the can immediately prior thereto dropping slightly until it rests on members 12 and 13. When the frame member is pushed rearwardly, finger 14 carried by the frame member will successively contact with members 12, 13 and the 15 frame member will contact with member 11, the said members thus being restored to initial position.

The modification illustrated in Figures 4 and 5 is of advantage when the device is applied to a 20 relatively thick shelf, and it is necessary that the can drop from the top of the shelf to a point below the same.

It will be understood that the means projected forwardly of the shelf during the movement of the row of containers and adapted to receive the foremost container when the latter is projected beyond the edge of the shelf and hold the container prior to its removal by the operator, may be applied to various kinds of devices for projecting the row of containers, and that the embodiment of the invention illustrated in the drawings is but one form of such means.

It will also be understood that by the term "caps" or "containers", I include any article 35 adapted to be placed in rows on a shelf and to which my invention is applicable.

Having described my invention, what I claim and desire to secure by Letters Patent, is as follows:—

40 1. Article projection apparatus for a shelf, comprising a plurality of frame members, each of rectangular bent formation and adapted to rest upon the top of a shelf, and each adapted to embrace a row of cans, and to move the row forwardly when the frame member is given a corresponding movement, and a plurality of slides supported by and below the shelf for horizontal sliding movement, one for each frame member, and each provided with supporting means for a 45 can, the slides each having a portion extended into the path of the foremost cans and being movable by the latter to a predetermined extent, so as to provide a support for the foremost can in front of the shelf.

50 55 2. Article projection apparatus for a shelf, comprising a plurality of frame members, each member being adapted to embrace a row of cans and having a contact section for the rearmost can whereby when the frame member is forwardly moved a predetermined distance on the shelf, the row of cans will be given a forward movement, a bracket member supported by and

5 below the shelf and a can support slidably held by said bracket member and having an upwardly bent section lying within a frame member in the path of the row of cans and having parallel rod-like extensions provided with means for engaging an abutment of the bracket member to limit the movement of the said support.

3. Article projection apparatus comprising a shelf provided with downwardly extending flanges, a frame member disposed upon the top 10 surface of the shelf and adapted to embrace a row of cans and having at its rear a contact section for engaging the rearmost can, whereby a movement of the frame member will forwardly project the row of cans, and a can support carried by said flanges for horizontal sliding movement and having a section projected within the path of movement of the foremost can, said section of the can support also lying rearwardly of an element of the frame member and within its 20 path of movement thereby being adapted for return movement by contact with said element of the frame member.

4. Article projection apparatus for a shelf, and in combination with a shelf, comprising a frame 25 member adapted to embrace a row of cans, and having a rearward contact element for engaging the rearmost can, a bracket member supported by and below the shelf and a plurality of can supports slidably held by said bracket member and adapted for successive substantially horizontal movement forwardly of the shelf, and means by which said successive movement of the can supports is transmitted to the latter by the frame member, comprising interengaging means between 30 the supports whereby the movement of one support will impart subsequent movement to a second support.

5. Article projection apparatus constructed in accordance with claim 4, in which the can supports comprise rods having horizontal sections and vertically bent sections, and inter-engaging means between the rods whereby the movement of one rod will impart subsequent movement to a second rod.

6. Article projection apparatus for a shelf, comprising a plate having depending flanges, the flanges being apertured to receive a plurality of rods, the rods being so formed that movement of one rod will subsequently impart movement to a second rod, a vertically bent section carried by one rod for engagement by a can, vertically bent sections carried by the remaining rods and disposed within and below the first-named vertical extension, means for attaching the plate to the undersurface of a shelf and a frame member adapted to embrace a row of cans and also adapted to embrace the first-named vertically extended member of the first named rod, and having a contact element for engaging the rearmost can 55 of the row.

WILLIAM V. WAXGISER.
